US0D1051732S

(12) **United States Design Patent** (10) **Patent No.:** **US D1,051,732 S**
(45) **Date of Patent:** **** Nov. 19, 2024**

(54) **TAMPON WRAPPER**

- (71) Applicant: **Edgewell Personal Care Brands, LLC**, Chesterfield, MO (US)
- (72) Inventors: **Andrew Schemetow**, Cedar Grove, NJ (US); **Blythe York**, Dover, DE (US); **Michael Burt**, Magnolia, DE (US)
- (73) Assignee: **Edgewell Personal Care Brands, LLC**, Chesterfield, MO (US)
- (**) Term: **15 Years**
- (21) Appl. No.: **29/958,284**
- (22) Filed: **Aug. 19, 2024**

Related U.S. Application Data

- (63) Continuation of application No. 29/873,214, filed on Mar. 28, 2023, now Pat. No. Des. 1,043,367.

(57) **CLAIM**

The ornamental design for a tampon wrapper as shown and described.

DESCRIPTION

FIG. 1 is a front perspective view of the tampon wrapper showing our new design;

FIG. 2 is a back perspective view thereof;

FIG. 3 is a side view thereof;

FIG. 4 is a side view thereof opposite to the side view of FIG. 3;

FIG. 5 is a back view thereof;

FIG. 6 is a front view thereof;

FIG. 7 is a top view thereof; and,

FIG. 8 is a bottom view thereof.

The broken line showing portions of the tampon wrapper is included for the purpose of illustrating environmental structure and forms no part of the claimed design.

1 Claim, 2 Drawing Sheets
